United States Patent Office.

THOMAS HOLT, OF BROOKLYN, NEW YORK, ASSIGNOR TO HIMSELF AND ABRAM T. MERWIN, OF SAME PLACE.

Letters Patent No. 91,635, dated June 22, 1869.

IMPROVEMENT IN GROOVING-MACHINE.

The Schedule referred to in these Letters Patent and making part of the same.

To all whom it may concern:

Be it known that I, THOMAS HOLT, of Brooklyn, in the county of Kings, and State of New York, have invented a new and useful Improvement in Grooving-Machines; and I do hereby declare that the following is a full, clear, and exact description thereof, which will enable others skilled in the art to make and use the same, reference being had to the accompanying drawings, forming part of this specification.

This invention relates to improvements in machinery for grooving stair-stringers, and other work in joinery and cabinet-making.

It consists in the combination and arrangement of parts hereinafter described.

Figure 1 represents a front elevation of my improved machine;

Figure 2 represents a plan view; and

Figure 3 represents a side elevation of the same.

Similar letters of reference indicate corresponding parts.

A represents the table of the machine, over which the boards or other articles to be grooved are fed by the feeding-rollers, the rollers being moved by hand or by any competent power.

C represents a rotary tool-stock, carrying saws D at each end for cutting the necessary kerfs for channelling out the grooves.

It also carries a planing or channelling-tool, E, for removing the substance between the saw-kerfs.

The said stock C is journaled upon slides F, arranged to slide in the adjustable ways, and provided with a handle, H, for moving the slides back and forth to traverse the board being grooved, which is fed under the tools intermittently by the roller B, as above described.

Motion is communicated to the tools by a belt, I, from an overhead shaft and pulley I¹, supported in the arms K, jointed to standard L, and to which arms N, pivoted to the shaft of the tool-stock, are also jointed, at P.

A pulley, J², is supported in the standards L, deriving motion from a pulley, Q, on the main driving-shaft, by belts passing around the guide-pulleys R R', and communicating motion to the pulley I¹ by the belt I.

The said guide-pulleys R R' are arranged upon a standard capable of adjustment around the axis of the driving-shaft.

The ways G are hinged at G', and the standards L are pivoted at L', for the purpose of adjusting the ways to the desired angle on the board, and for maintaining

the driving-belts and pulleys in their proper working-positions.

The bolts T, working in the curved slots T', are for securing the ways in any required position; and adjustable stops U are provided in the outer ends of the ways for governing the outward movement of the slides when it is designed to cut the grooves only partly across the board.

W represents a spring-gauge or stop, arranged upon a swinging arm, W', to be employed for catching into the formed grooves, as the board is moved along, when a number of grooves is to be formed at regular intervals, to arrest and hold the boards. It also serves to determine the distance required between each groove, and is arranged to be adjusted to any distance from the grooving-tools.

I propose to arrange one of these stops on each side of the swinging frame or ways G.

X represents a screw-clamp, designed for screwing down upon the boards when desired for holding them more firmly.

In grooving stair-stringers, which have two grooves converging at a given point, and running in opposite directions on the board, the ways G are first adjusted for cutting the grooves in one direction, and the board is passed through, receiving all the grooves in that direction. The ways are then adjusted to the other direction, for the other groove, and the work proceeded with as before.

Holes may be bored at the point of intersection of the grooves, to give any desired form thereto, as in the ordinary method of forming such grooves by hand.

Having thus described my invention,

I claim as new, and desire to secure by Letters Patent—

1. The oscillating standard L, arms K N, carrying the pulleys I I', and the slides F, for carrying the cutter, in combination with the swinging frame, all arranged and operating as described, for the purpose specified.

2. The adjustable standard and guide-pulleys R R', in combination with the oscillating standard L, pulley I², main driving-belt, and the driving-pulley Q, all arranged and operating as described, for the purpose specified.

The above specification of my invention signed by me, this 28th day of December, 1869.

Witnesses:

THOMAS HOLT.

FRANK BLOCKLEY,
ALEX. F. ROBERTS.
